COMBINED TOOTHPICK AND DENTAL FLOSS HOLDER

Christopher G. Chinque, 3 Schillerstrasse,
6203 Hochheim am Main, Germany

Filed Mar. 31, 1975, Ser. No. 563,772

Term of patent 14 years

Int. Cl. D24—99; D28—03
U.S. Cl. D86—10 D

Fig. 1

Fig. 2

Fig. 4

FIG. 1 is a bottom plan view of a combined toothpick and dental floss holder showing my new design;

FIG. 2 is an edge elevational view thereof;

FIG. 3 is a top perspective view thereof; and

FIG. 4 is a right end elevational view thereof.

I claim:

The ornamental design for a combined toothpick and dental floss holder, as shown and described.
